OF NEW YORK, N. Y., A CORPORATION OF NEW YORK.

TOY WAGON.

1,244,506.

Specification of Letters Patent.

Patented Oct. 30, 1917.

Application filed January 26, 1917. Serial No. 144,589.

To all whom it may concern:

Be it known that I, LOUIS H. KIRK, a citizen of the United States, and resident of New York, in the county of New York and State of New York, have invented certain new and useful Improvements in Toy Wagons, of which the following is a specification.

This invention relates to toy wagons, and particularly to toy wagons of the "knock-down" type; the main object of the invention being to provide a toy wagon that may be readily knocked down or taken apart to occupy a minimum space for convenience in packing and transportation, and which subsequently can be as readily restored to its normal condition, and both of which operations may be effected by hand and without the use of tools of any kind.

20 In a toy wagon embodying my invention the usual axle and handle of which are attached to the under side of the body, are so constructed and mounted as to be capable of being folded from their normal operative positions projecting beyond the edges of the body to inoperative positions wholly beneath the body, whereby, when the wagon as a whole is knocked down and the wheels are placed within the body, it will occupy 30 practically only the space taken up by the body.

A wagon embodying my invention is illustrated in the accompanying drawings, in which—

35 Figure 1 is an inverted plan view of the wagon when set up for use, and also showing in dotted lines the folded or knocked down position of the axle and handle.

Fig. 2 is a side elevation of the wagon in 40 its knocked down condition for packing or transportation, and also showing in dotted lines the normal or operative position of the parts when set up for use.

Fig. 3 is a plan view of the wagon in its 45 knocked down condition as shown in Fig. 2, with the detachable wheels and a part of the handle placed within the body of the wagon.

Fig. 4 is an enlarged sectional detail on the line 4—4 of Fig. 1.

Similar reference characters indicate like parts on the several figures of the drawings.

The toy wagon as illustrated comprises an open rectangular body 2 of usual construction. Attached to the under side of this body is a transversely arranged axle 3 which projects at its ends beyond the opposite sides of the body and has journaled thereon the wheels 4, which latter are here shown as removably retained on the axle by suitable fastening pins 5.

The axle 3 may be attached to the body 2 in any suitable manner to permit of its being adjusted from an operative position with its ends projecting beyond the body in wheel-engaging position, to an inoperative 65 position beneath the body when not in use. In the present case, it is held by two clamping bolts 6 and 7, extending through holes in the same, one of which holes is open-sided, as at 8. Thus, when the wagon is set up for 70 use, as shown by full lines in Fig. 1, the axle is firmly held in place by its said clamping bolts. When, however, it is desired to knock down or disassemble the wagon for packing or transportation, the wheels 4 are 75 removed from the axle and the fastening bolt loosened, after which the axle is swung on the bolt 6 as a pivot to be first disengaged from the bolt 7 through the open-sided slot 8 and then brought to a position beneath the 80 body and lengthwise of the same, as shown by dotted lines in Fig. 1, in which position it may be held by tightening up the bolt 6.

The tongue or handle for the wagon, indicated at 10, is attached to the under side of 85 the body 2 in a manner similar to that of the axle 3, whereby it may also be adjusted to a position wholly beneath the body for packing or transportation purposes. As shown, the handle is held in operative position by two fastening or clamping bolts, 11 and 12, extending through holes in the same, one of which holes is open-sided as at 13.

By loosening these bolts, the handle may 95 be readily swung on the bolt 11 from its operative position projecting beyond the front end of the body, as shown by full lines

in Fig. 1, to an inoperative position wholly beneath the body, as shown by dotted lines in said Fig. 1, this movement being readily permitted by disengagement of the handle from the bolt 12 through its open-sided slot 13. When the handle is swung to its inoperative position beneath the body, it may be held in such position by a tightening up of the bolt 11.

10 The handle proper, 10, is preferably made of such length as not to project beyond the edges of the body when moved to a position beneath the same. In some cases, it may happen that the operative length of handle 15 thus provided is not sufficient, as might be the case if the wagon were being used by large children. Therefore, to provide a sufficient length of handle for any contingency, I provide an extension piece or section 14 20 which is detachably connected to the end of the main handle 10 by a suitable fastening device, such as the clamping bolt 15. When this handle extension 14 is provided, it is preferably made of a length to conveniently fit within the body, as shown in 25 Fig. 3, when the wagon is knocked down and the main handle swung to its inoperative position beneath the body.

With the construction shown and described, it will be clear that the wagon can be readily set up for use and knocked down for packing or transportation and this without the use of tools of any kind.

What I claim is:—

35 1. A toy wagon of the knock-down type, comprising a body, a supporting axle therefor having wheels detachably journaled on its opposite ends, said axle being adjustably connected with the body for movement from an operative position with its ends projecting beyond the body to an inoperative position beneath the body, and means for adjustably holding the axle in its operative and inoperative positions.

45 2. A toy wagon of the knock-down type, comprising a body, a supporting axle therefor having wheels detachably journaled on its opposite ends, said axle being pivotally connected with the body for swinging movement from an operative position with its ends projecting beyond the body to an inoperative position beneath the body, and means for adjustably holding the axle in its operative and inoperative positions.

55 3. A toy wagon of the knock-down type, comprising a body, a supporting axle therefor having wheels detachably journaled on its opposite ends, and clamping devices adjustably holding said axle to the body and 60 on one of which the axle turns for movement from an operative position with its ends projecting beyond the body to an inoperative position beneath the body.

4. A toy wagon of the knock-down type,

comprising a body, a supporting axle therefor having wheels detachably journaled on its opposite ends and also having a pair of bolt holes one of which is open-sided, and clamping bolts engaging the axle through its said holes for adjustably holding the same to the body and on one of which bolts the axle turns for movement from an operative position with its ends projecting beyond the body to an inoperative position beneath the body, and the other of said bolts being disengagable from the axle through the open-sided hole therein upon the said movement of the axle from operative to inoperative position.

5. A toy wagon of the knock-down type, comprising a body, a supporting axle therefor having wheels detachably journaled on its opposite ends and being of less length than the length of the body, said axle being adjustably connected with the body for swinging movement from an operative position with its ends projecting transversely beyond the body to an inoperative position beneath and lengthwise of the body, and means for adjustably holding the axle in its operative and inoperative positions.

6. A toy wagon comprising a wheeled body having a handle, said handle being formed in two sections detachably connected together and one of which is adjustably connected with the body for movement from an operative position projecting forward of the body to an inoperative position beneath the body.

7. A toy wagon comprising a wheeled body having a handle, said handle being formed in two sections detachably connected together and one of said sections having a pair of bolt holes one of which is open-sided, and a pair of clamping bolts engaging the handle through its said holes for adjustably holding the same to the body and on one of which bolts the handle turns for movement from an operative position projecting beyond the body to an inoperative position beneath the body, and the other of said bolts being disengagable from the handle through the open-sided hole therein upon the said movement of the handle from operative to inoperative position.

8. A toy wagon comprising a body having side and end walls, a supporting axle therefor having wheels detachably journaled on its opposite ends, said axle being adjustably connected with the body for movement from an operative position with its ends projecting transversely beyond the body to an inoperative position beneath the body and said wheels being of a size to fit within the body when detached from the axle, a handle formed in two sections detachably connected together and one of which is adjustably connected with the body for move-

ment from an operative position projecting forward of the body to an inoperative position beneath and lengthwise of the body, and the other of which sections is of a length 5 to fit within the body when detached from the first-named section.

Signed at New York, in the county of

New York, and State of New York, this 25th day of January A. D. 1917.

LOUIS H. KIRK.
